CLAIM

We claim the ornamental design for an aircraft, as shown and described.

DESCRIPTION

FIG. 1 is a perspective view taken from a top, front, and left side of an aircraft.

FIG. 2 is a front view of the aircraft of FIG. 1.

FIG. 3 is a rear view of the aircraft of FIG. 1.

FIG. 4 is a left view of the aircraft of FIG. 1.

FIG. 5 is a right view of the aircraft of FIG. 1.

FIG. 6 is a top view of the aircraft of FIG. 1; and,

FIG. 7 is a bottom view of the aircraft of FIG. 1.

In the drawings, the claimed design is defined by the shaded surfaces; broken lines immediately adjacent shaded surfaces represent boundaries of the claim and form no part thereof; all other broken lines depict portions of the aircraft that form no part of the claim.
